CLAIM

The ornamental design for a foam dispenser, as shown and described.

DESCRIPTION

FIG. 1 is a bottom view of the form dispenser of the present invention; and,

FIG. 2 is a front view of the foam dispenser of the present invention.

The undisclosed side opposite that shown in FIG. 2 is substantially the same as the image shown in FIG. 2.

The surface(s) or portion(s) of the article not shown in the drawing or described in the specification form(s) no part of the claimed design.
